AUTOMATIC DRAIN VALVE

Clyde C. Farmer, Pittsburgh, Pa., assignor to The Westinghouse Air Brake Company, Wilmerding, Pa., a corporation of Pennsylvania

Application May 27, 1943, Serial No. 488,670

3 Claims. (Cl. 303—88)

This invention relates to compressed air systems, and more particularly to automatic drain valve means operative to discharge condensate accumulating in the storage reservoir of an air brake system.

Various designs of inexpensive drain valves have been proposed for effecting intermittent discharge of condensed moisture from air storage reservoirs, such as the main reservoir forming part of an air brake equipment on a locomotive, where accumulation of water from the compressed air constitutes a well known source of operating difficulties. Although certain types of drain valve devices have proven satisfactory while new and operating under favorable service conditions, excessive loss of air and other difficulties may be experienced after wearing of parts has become advanced. Thus there still remains a need for a sturdy and reliable drain valve apparatus constructed and arranged to discharge condensate from a reservoir during measured intervals automatically timed in accordance with a recurring operating condition, such as application of the brakes.

It is a principal object of my invention to provide an improved automatic drain valve apparatus of the class above described comprising condensate discharge valve means so constructed and arranged as to reduce to a minimum the leakage of air while the drain valve apparatus is inoperative, and fluid pressure timing means for automatically regulating the interval during which the discharge communication remains open.

Another object of the invention is to provide an improved drain valve device having the characteristics just mentioned and adapted to operate in response to each application of the brakes of the locomotive.

The advantages and novel features of the invention will be better understood upon consideration of the following detailed description, taken in connection with the accompanying drawing, wherein

Fig. 1 is a diagrammatic sectional view of an automatic drain valve device constructed in accordance with one form of the invention;

Fig. 2 is a diagrammatic sectional view of a drain valve device embodying the invention in a different form; and

Fig. 3 is a similar view of a drain valve apparatus, mainly in section, exhibiting the features of a third species of the invention.

Apparatus in Figure 1

The equipment shown in Fig. 1 includes a main reservoir 5, which is of the type usually carried on a locomotive and supplied with compressed air by a compressor (not shown), a brake cylinder 6, and an automatic drain valve device

7 arranged to collect and discharge condensate from the reservoir in response to the pressure of air supplied to the brake cylinder.

The drain valve device 7 comprises a pipe bracket 10 having bolted or otherwise secured thereto a casing section 11 in which is formed a valve chamber 12 communicating with an atmospheric port 13. Mounted in the valve chamber 12 is a slide valve 15 which is yieldingly held on a seat 16 under the force of a spring 17 that is interposed between an upper wall of the valve chamber and a collar carried by a strut 18. For operating the slide valve there is provided a lever 20 having one end pivotally connected to the valve and the other end journaled on a pin 21 carried by the casing structure, and operatively connected by an intermediate pin 22 to a follower member 23, one end of which is slidably mounted in a bore 24 formed in a cap member 25 secured to the casing 11. The other end of the follower member 23 is secured to a flexible diaphragm 27 which is interposed between the casing section 11 and a cover section 28, and which is subject to the opposing forces of fluid pressure in a chamber 30 formed at the outer face of the diaphragm and the pressure of a spring 31 interposed between follower 23 and the cap member 25. The diaphragm chamber 30 communicates by way of a passage and pipe 34 with the supply pipe 35 leading to the brake cylinder 6.

When the air brakes are released and the brake cylinder pipe 35 is vented to the atmosphere in the usual manner, the spring 31 is effective to hold the follower member 23, diaphragm 27 and slide valve 15 in the normal position in which these elements are shown in Fig. 1. Condensed moisture is at this time free to flow from the main reservoir 5 into a drain chamber 38 formed in a casing section 39 carried by casing section 11, by way of a pipe 40, a passage 41, a cavity 42 in the slide valve, and a passage and tube 43 opening at the bottom of the drain chamber. At the same time, a second cavity 46 in the slide valve is positioned for connecting the vented brake cylinder passage 34 to a passage 47 communicating with a timing chamber 48, which is formed in the casing section 11.

When an application of the brakes is effected compressed air is supplied in the usual manner through the brake cylinder pipe 35 to the brake cylinder 6, and also flows by way of the pipe and passage 34 to the diaphragm chamber 30, and by way of cavity 46 and passage 47 to the volume chamber 48. The volume chamber 48 is thereby charged with air under pressure until the fluid pressure acting on the diaphragm 27 is increased to the predetermined value required for overcoming the opposing force of spring 31, whereupon the diaphragm, follower member 23, and

slide valve 15 are shifted to the right, as viewed in Fig. 1. When the slide valve 15 is thus moved into engagement with a stop lug 50 formed on the casing, the communication between the brake cylinder and the volume chamber 48 is cut off, while communication is established between that chamber and drain chamber 38 by way of passage 47, cavity 46, and a passage 51. At the same time the passage 43 is connected through the cavity 42 with an atmospheric discharge passage 53, with the result that the water previously deposited in the drain chamber 38 is driven out through the tube and passage 43, cavity 42 and discharge passage 53, under the pressure of air with which both chambers 38 and 48 have been charged. Compressed air is prevented from escaping from the main reservoir 5 at this time, since the slide valve 15 has been positioned to close the passage 41.

When the brakes are released, compressed air is vented from the brake cylinder 6 and diaphragm chamber 30 by way of the pipe 35, and other communications established by the usual brake controlling valve. The spring 31 is then rendered effective to return the follower member 23 and slide valve 15 to the positions in which they are shown in Fig. 1. The slide valve is thus operated to reestablish the drain communications hereinbefore described and through which condensate is forced from the main reservoir into the drain chamber 38 in the automatic drain valve device, and the apparatus is then conditioned for another cycle of operation.

Apparatus in Fig. 2

Illustrated in Fig. 2 is a modified form of automatic drain valve device 57 having a casing structure made up of casing sections 58, 59 and 60, which may be bolted or otherwise secured together by suitable means, not shown. Clamped between the casing section 59 and the respective sections 58 and 60 are a pair of similar flexible diaphragms 63 and 64, which are connected together through the medium of a follower member 65 and urged upwardly, with diaphragm 63 engaging a stop boss 66 as shown in the drawing, under the force exerted by a coil spring 67 that is interposed between the follower member and a partition 68 formed in the casing section 60. Between the diaphragms is a valve chamber 70 communicating by way of a pipe 71 with the main reservoir 5a, and which has mounted therein a slide valve 73 that is held on a valve seat 74 through the medium of a spring 75 and a strut member 76. The strut member 76 is journaled on a pin 77 carried by the casing section 59, and is pivotally connected by means of a pin 79 to the follower member 65, which is thus adapted to actuate slide valve 73 through the medium of the strut member.

At the upper side of the diaphragm 63 is formed a chamber 80 which communicates by way of a pipe 81 with the brake cylinder 6a. Formed within the casing section 60 is a chamber 83 which is disposed intermediate the diaphragm 64 and the partition 68 and is connected to the atmosphere through a port 84. A drain chamber 85 is also provided in the casing section 60 in association with a passage 86 leading from the lowermost portion thereof to the seat of the slide valve.

So long as the brakes are released and the brake cylinder 6a, pipe 81, and chamber 80 are connected to the atmosphere, the coil spring 67 remains effective to hold the follower member

65, diaphragms 64 and 63, and slide valve 73 in their normal positions, as shown in the drawing. With the slide valve 73 in the normal position, a drain communication is maintained between the lowermost portion or sump of the main reservoir 5a and the drain chamber 85 in the drain valve device, by way of a pipe and passage 88, a cavity 89 in the slide valve, and passage 86, so that condensate accumulated in the reservoir is free to flow into the drain chamber. It will be understood that since the intermediate chamber 70 is connected with the main reservoir 5a, the reservoir pressure is equally distributed in opposing directions over the two diaphragms 63 and 64, and is thus not effective to control the positioning thereof. The reservoir pressure in chamber 70 is, however, effective to maintain the slide valve 73 properly positioned on the seat 74.

When compressed air is supplied to the brake cylinder pipe 81 for causing an application of the brakes, the fluid pressure acting on the diaphragm 63 is built up sufficiently to overcome the opposing force of the spring 67, and the associated diaphragms and the follower member 65 are then moved downwardly until a follower plate 65a at the lower face of diaphragm 64 is brought into engagement with the partition 68. In so moving, the follower member 65 operates the strut 76 through the medium of the pin 79 for moving the slide valve 73 to a new position, wherein communication between the reservoir pipe 88 and passage 86 is cut off, while the passage is connected to a discharge port 90. Air previously stored up at main reservoir pressure in drain chamber 85 thereupon drives out the condensate by way of the passage 86, slide valve cavity 89, and discharge port 90.

Upon release of the compressed air from the brake cylinder and consequently from the diaphragm chamber 80 of the drain valve device, the spring 67 is rendered effective to shift the diaphragm assembly and the slide valve 73 into the normal position in which these elements are shown in Fig. 2, thereby reestablishing the original communications already described.

Apparatus in Figure 3

Illustrated in Fig. 3 is an automatic drain valve device embodying features of the invention in a form enabling the mounting of the device in close association with the main reservoir inlet connection, so that the possibility of freezing of the parts will be minimized due to conduction thereto of heat of compression from the air being supplied to the reservoir from the usual compressor. The apparatus shown in Fig. 3 includes an air compressor indicated generally by the reference character 100, which is operative to supply compressed air to a main reservoir 5b by way of a compressor discharge pipe 101, a drain valve device 102, and the usual brake cylinder 6b. The casing structure of the drain valve device 102 includes a casing section 105 and a pipe bracket 106, the latter of which has integrally formed thereon an extension which constitutes a pipe union portion 108 forming part of the air conduit assembly connecting the compressor 100 to the main reservoir 5b. The pipe union portion 108 has a suitable flange adapted to be secured to an end wall 110 of the main reservoir by means of bolts 111. The pipe union assembly is completed by a clamping ring 113 and an annular nut 114 which are adapted to be secured to the portion 108 of

adjacent end of compressor discharge pipe 101. Formed in the casing section 105 is a valve chamber 116 which is adapted to receive condensate from the main reservoir 5b by way of a passage 118 formed in casing section 105 and pipe bracket 106, and a siphon tube 119 having its upper end suitably connected to the reservoir end wall 110 and its lower end opening adjacent the bottom of the reservoir. Mounted within the chamber 116 is a follower member 120, which is operatively connected to a slide valve 121, and has an annular seat rib 122 that is adapted to be held in engagement with a gasket 123 carried by the casing section, when the follower member is maintained in a normal position under the force of a coil spring 124, as shown in the drawing. The spring 124 is interposed between a hollow plunger 125 abutting follower member 120, and a cap member carried by the end of the casing section 105. The slide valve 121 is operative to control communication between the valve chamber 116 and a drain passage 126, as hereinafter explained. A coil spring 127 is preferably interposed between the follower member 120 and the slide valve for maintaining the latter in proper engagement with its seat.

For actuating the slide valve assembly there is provided a piston 130, which is slidably mounted in a suitable bore in the casing section 105, forming on one side thereof a pressure chamber 131 which communicates through a passage and pipe 132 with the brake cylinder 6b. At the opposite side of the piston 130 is formed a chamber 133 opening into a timing chamber 135, which communicates by way of a restricted passage 136 with passage 132. An annular seat rib 138 is formed on the piston 130 within chamber 133 and in operative alignment with a gasket 139, which is disposed adjacent a bore in the casing section through which extends a piston stem 140 that engages the follower member 120.

In operation, compressed air supplied to the brake cylinder 6b, in effecting an application of the brakes, flows through the pipe and passage 132 to the piston chamber 131, and moves the piston 130, follower member 120 and slide valve 121 to the right, as viewed in Fig. 3, overcoming the force exerted by the coil spring 124 against plunger 125. With the slide valve 121 in this position, a cavity 145 therein connects a passage 146 with the drain passage 126, with the result that condensate accumulated in the main reservoir 5b is driven out by way of the siphon tube 119, passage 118 in the drain valve device, valve chamber 116, and the said communication 146, 145 and 126.

It will be understood, however, that the slide valve 121 is maintained in the discharge position only for the interval of time required for the build up of fluid pressure in the timing chamber 135 and chamber 133 by flow of compressed air through the restricted passage 136. As this fluid pressure approaches that of the air in piston chamber 131, the spring 124 is rendered effective to move the plunger 125, follower member 120, slide valve 121, and piston 130 back to the normal positions in which these members are shown in Fig. 3. The reservoir drainage communication is thus cut off in time to prevent undesired waste of compressed air from the main reservoir. The

drain valve device 102 is thus operative in response to an increase in brake cylinder pressure to permit discharge of condensate from the main reservoir for a limited interval of time, the cycle of operation of the slide valve element from its closed position to its opened position and then back to the closed position being completed independently of the pressure of air maintained in the brake cylinder.

From the foregoing description of three structurally different drain valve devices embodying my invention, there are thus exhibited some of the advantages obtainable by the association with a compressed air storage reservoir of a drain valve assembly including a loaded slide valve controlling a drainage outlet, and fluid pressure responsive actuating means for effecting quick and positive movement of the slide valve through an operational cycle requiring only a small quantity of compressed air.

Having now described my invention what I claim as new and desire to secure by Letters Patent, is:

1. The combination with a main reservoir and a brake cylinder in an air brake equipment, of a drain valve device comprising a casing having a drain passage and a discharge port, a spring, a movable abutment subject to the opposing pressures of air in the brake cylinder and of said spring, and a slide valve actuated by said movable abutment and operative to establish communication between said drain passage and said discharge port, said slide valve being constructed and arranged to be constantly loaded under the pressure of air in said reservoir.
2. The combination with a main reservoir and a brake cylinder in an airbrake equipment, of a drain valve device comprising a casing having a piston chamber communicating with said brake cylinder and a timing chamber also communicating therewith by way of a restricted port, a slide valve mounted in said casing for controlling a drainage communication through which condensate can be discharged from said main reservoir, said slide valve being constantly loaded under the pressure of air in said reservoir, a spring for normally positioning said slide valve means to close said drainage communication, and a piston subject to the opposing pressures of fluid in said piston chamber and of fluid in said timing chamber, said piston being responsive to an increase in brake cylinder pressure for operating said valve means to open said drainage communication for a limited time.
3. The combination with a main reservoir and a brake cylinder in an air brake equipment, of a drain valve apparatus including a casing structure carried by the main reservoir and having a drainage communication, a siphon tube mounted within said reservoir and having one end opening adjacent the bottom wall thereof and the other end connected to said discharge communication, a slide valve mounted in said casing for normally closing said drainage communication, said slide valve being constantly loaded under the pressure of air in said reservoir, and movable abutment means constructed and arranged to respond to an increase in brake cylinder pressure for operating said valve to open said drainage communication for a predetermined interval.

CLYDE C. FARMER.
